Inventor

Daniel E. Kempster.

UNITED STATES PATENT OFFICE.

DANIEL E. KEMPSTER, OF BOSTON, MASSACHUSETTS.

SPRING SHADE-ROLLER.

SPECIFICATION forming part of Letters Patent No. 286,302, dated October 9, 1882.

Application filed September 18, 1882. (No model.)

To all whom it may concern:

Be it known that I, DANIEL E. KEMPSTER, a citizen of the United States, residing at Boston, in the county of Suffolk and State of Massachusetts, have invented certain new and useful Improvements in Spring Shade-Rollers; and I do hereby declare that the same are fully described in the following specification and illustrated in the accompanying drawings.

My invention relates to that class of shade-rollers in which a coiled spring located in the roller is employed to raise and sustain the curtain or window-shade; and it consists in an improvement in the construction of the brackets, and also on the construction and arrangement shown in United States Patent No. 183,809, granted to A. H. Knapp. In the above patent one or more pins are driven into the end of the shade-roller, and a pivoted pawl, operated by centrifugal force, engages the aforesaid pins and locks the spring from unwinding when the roller is removed from its brackets. Now, I prefer to use rings with stops on their inner sides, and having spurs or means on the back to attach itself to the roller end instead of the pins driven into the roller end. The rings are held in position and the roller end is prevented from splitting by a metal cap; but, if desired, pins may be driven in as heretofore, and the metal cap covers them up and protects the roller end from injury. In the above patent referred to the plate, which is attached to the spindle, and on which the centrifugal pawl is pivoted, is provided on its outer face with a projection. A corresponding projection is arranged on the inner face of the bracket. The former is arranged to strike the latter, and thereby prevent the insertion of the spindle in the bracket-notch, except when the spindle is right side up, to bring the pawl into a self-gravitating position for keeping it out of contact with the pins or projections on the roller end. Now, the objections to the above arrangement are: It necessitates great care and accuracy in the making and putting together the several parts, for if the brackets vary in thickness or the notch in the spindles varies in width, the projections on the bracket and pawl-plate are very liable to either be so far from each other or so near to each other as to completely destroy the object for which they are intended; also, a very great

objection is the locking device arranged on the outside of the roller end, where it must necessarily be when said locking device is constructed with projections intended to come in contact with corresponding projections on the bracket, and thus insure its being placed in said brackets right side up. Such arrangements cannot be covered up and protected by a metal ferrule, and in the ordinary handling in transportation are constantly becoming broken or bent out of shape, so as to be inoperative. Furthermore, rollers without ferrules, and having pins or projections driven into their ends for the pawl or lock to strike or catch against by the force of the spring, are very liable, and do frequently, split out the ends of the rollers, especially after they have been up to the windows some time and become thoroughly dry and brittle, and more especially if the spring is a moderately heavy one.

Now, my improvement has for its object to overcome all these objections and produce a more simple and durable roller, which will be less liable to get out of order, which I accomplish in the following manner, reference being had to the accompanying drawings, on which—

Figure 1 is a sectional elevation of the shade-roller resting in its brackets. Fig. 2 is a cross-section on the line V W shown in Fig. 1, the centrifugal pawl being shown as locked. Fig. 3 is an end view seen from U in Fig. 1. Fig. 4 is a section on the line x y shown in Fig. 3. Fig. 5 is the pawl or lock-plate, and its pawl or lock. Fig. 6 is the ring-stop. Fig. 7 is a modification of my improvement, as will be more fully described. Fig. 8 is the brackets.

In the drawings, *a* represents the curtain or shade roller. *b* is the tubular roller end cap. *c* is the fixed spindle at the spring end of the roller, and *d* is the bracket in which said spindle is mounted. The tubular end cap, *b*, is preferably made of hard wood, and forms a part of the roller *a*, and it is bored through considerably larger than the spindle *c*. The bore is enlarged on the inner side, and extends in, leaving a sufficient thickness, *b'*, of the cap for holding the pins or ring-stop *b''*, which are attached to the end cap, *b*. The shell or portion of the cap *b* which has the enlarged bore enters into and is inclosed within the bore of the roller *a*. On the spindle *c*, and within the said shell, and next the portion *b'* of the cap *b*,

is an enlarged journal of felt, a' , or friction material such as claimed in United States Patent No. 251,893, granted to me January 3, 1882. A washer, c'' , is interposed between said journal and the portion b' of the cap. On the spindle c , outside of the cap b , is a fixed plate, e , on which a loose pawl, f , is pivoted. The spindle c rests in the bracket d , with the pawl f uppermost, as shown in Figs. 1 and 2, so that 10 said pawl by its own gravity will drop away from the stops b'' , and remains out of contact therewith as long as the roller is mounted in its brackets, and thus not interfere with the revolution of the roller therein. The pawl f rests over the spindle in this position: The 15 end of the spindle c is provided with a lip, c''' , on one side, which fits a corresponding cavity, d' , in one side of the notch on the bracket d , thus insuring its being put in only one way— 20 right side up. Now, having transferred the co-operating projection from the pawl-plate e to the end of the spindle itself, I am enabled to cover the aforesaid centrifugal locking device and roller end with a metal ferrule, h , and 25 thus protect it from injury; and to give both ends of the roller the same finished appearance, I also place a metal ferrule over the end block, on which is the journal a' . When 30 the spindle c is taken from the bracket by removing the roller, the spring g in the roller immediately revolves the spindle, whereby 35 centrifugal action is imparted to the pawl f , causing it to fly out and engage one of the stops b'' and prevent any further uncoiling of the spring. This spring, as will be seen by reference to Fig. 1, is formed with refolded or 40 redoubled layers, and the ends of the same are fastened to the cap b and the spindle c , respectively. As shown in Fig. 1, the solid end 45 of the roller a has a hard-wood end block, with a journal, a' , which runs loosely in a friction-bearing or ring of felt, a'' , contained in the ring a''' of the bracket a''' . As shown in Fig.

5, I make the pawl-plate e with ears e' for overlapping and loosely holding the pawl or 45 lock, but without any projections for engagement with the bracket. It will also be seen that the ferrule h comes up to and in contact with the stops b'' , thus securely holding them 50 in place and preventing the pawl from ever slipping over the ends of said stops, as is frequently the case when the spindle c has a little too much end-play in the roller a . The spring g is balanced by the felt frictional journal and bearing aforesaid, and a weighted bottom slat in the shade or curtain. 55

The modification shown in Fig. 7 is the device adapted as a stop-roller by being turned upside down, the lip on the spindle end being made on the opposite side, and thus holds it 60 in the bracket in that position. As shown in Fig. 8, the brackets d , d''' , and I are constructed with a single screw-hole drawn-foot with prods j . What I mean by a "drawn-foot" is one which is so shaped as to be capable of 65 being drawn from the mold and leave said mold in a condition to cast the foot complete with screw-hole, thus save the necessity of any drilling. The bracket I has a tapering pivot, i , and is used with an end block having a central hole, this being preferable in some cases where less friction is required than when the journal a' and ring-head bracket a''' are used. 70

What I claim is—

In a spring shade-roller, the combination of 75 the roller a , spindle c , provided with the lip c'' , pawl f , pawl-plate e , cap b , with stops b'' , washer c'' , journal c' , spring g , journal a' , and the metal cap or ferrule h , as set forth.

In testimony whereof I have affixed my signature in presence of two witnesses. 80
